METHOD OF AND MACHINE FOR MAKING PAPER

Application filed June 20, 1931. Serial No. 545,711.

This invention relates to a method of and machine for making paper, its object being to produce paper having more nearly uniform physical characteristics, especially tear 5 resistance and folding endurance, than those found in ordinary papers.

One of the major defects likely to exist in paper as ordinarily produced is that the web of paper taken off the paper machine in- 10 variably possesses different physical characteristics in its lengthwise and crosswise direc- 15 tions. This is true of papers produced on either a cylinder or Fourdrinier type of paper machine, as in the case of papers pro- 20 duced on both these types of machines there is usually lack of sufficient cross-lying fibers to make for the desired uniform texture. while in the case of a cylinder-machine-made paper this condition may sometimes be so 25 serious that splits or tears are easily produced lengthwise of the paper web, nevertheless it obtains also in Fourdrinier-machine- 30 made papers, despite the fact that the Fourdrinier machine may include mechanism for 35 shaking the forming wire or its other parts in order to offset the pronounced tendency for the fibers to assume a longitudinal lay, i. e., in the machine-direction. When one 40 considers the conditions under which paper 45 is formed even on a Fourdrinier machine, it is not surprising that the fibers tend to assume a preponderantly longitudinal lay. Thus, it is usually the practice to flow the 50 pulp suspension onto the forming wire at a rate of speed substantially equal to that of the forming wire, so that when the pulp sus- 55 pension reaches the wire, the fibers have a longitudinal component of motion with com- 60 paratively little lateral component of motion, especially at high papermaking speeds. The effect of a lateral component of motion imparted by shaking means after the sus- 65 pension is already on the wire is in practice usually insufficient to offset the decided ten- 70 dency for the fibers to arrange themselves lengthwise on the wire and to retain this ar- 75 rangement.

In accordance with my invention, I im- 80 part to the flowing stream of pulp suspen- 85 sion, preferably just before it is deposited

on the traveling forming wire or equivalent instrumentality, a lateral or so-called across-direction component of motion approximating that of the so-called machine-direction component, so as to produce a finished paper 55 having substantially the same physical characteristics in the across-direction as in the machine-direction. In fact, the fibers assume an effective diagonal lay in the finished paper, rather than a predominating longitudinal or machine-direction lay, as usual. By my invention, the effective lay may be made to approach 45° to both the machine-direction and the across-direction. The flowing stream of pulp suspension, to which both 60 components of motion have been imparted in accordance with my invention, is preferably deposited on the forming wire or equivalent instrumentality immediately above a suction 65 box or analogous dewatering device, whereby the suspension is reduced as quickly as possible to a quasi-dough-like consistency, so as to inhibit the tendency for the fibers to undergo rearrangement in their further course 70 on the paper machine. In other words, the 75 fibers are preferably largely fixed in their prearranged state immediately upon contacting with the web-forming instrumentality. While it is possible to give the flowing stream 80 of pulp suspension a lateral component of motion in various ways, I prefer to do this by causing a belt or its equivalent to move directly under the stream in a direction sub- 85 stantially perpendicular to the direction of flow immediately before the stream reaches the web-forming instrumentality. The belt is preferably of a width or girth to make considerable area of contact with the stream, its 90 contacting area, speed of travel, kind of surface, etc., being coordinated with the speed of the papermaking machine, so as to throw a sufficient proportion of the fibers in the across-direction. The belt can be made of thin, flexible sheet metal, rubber, or other 95 preferably water-impermeable material, and can be suitably roughened or grooved transversely of its direction of travel to promote impartation to the stream of the desired predetermined lateral component of motion.

With the foregoing and other features and 100

objects in view, I shall now describe in greater detail the application of the principles of my invention. While not limited thereto, a Fourdrinier type of paper machine has been chosen for purposes of illustration on the accompanying drawing, wherein

Figure 1 is a plan view of the wet end of the machine equipped with a cross-feed for the stream of pulp suspension immediately adjacent to the pulp-depositing station.

Figure 2 represents a longitudinal section through the wet end.

Figure 3 illustrates conventionally and diagrammatically the use of opposite cross-feeds at the wet end of a machine having a pair of separate pulp-depositing stations.

Referring first to Figures 1 and 2 of the drawing in detail, 1 represents the traveling wire cloth of the machine, which, as best shown in Figure 2, passes successively over a breast-roll 2, a series of table-rolls 3, a suction box 4, and some more table-rolls 5. Between the last of the series of rolls 3 and the suction box 4 is shown a cross-feed belt 6, the front edge of which terminates directly over the box. The belt may be mounted upon a pair of terminal pulleys 7, one or both of which may be driven by suitable means (not shown) so as to propel the belt crosswise of the direction of travel of the wire as indicated by arrow. The pulleys are somewhat spaced from the side edges of the wire and can be arranged, as shown, at an elevation to cause the belt to clear the wire with as little a gap or clearance as possible. It is the belt 6 which serves as the means for imparting a lateral component of motion to the continuous stream of pulp flowing onto the wire, for the belt moves directly in contact with the stream and at right angles thereto immediately before the stream reaches the wire. In fact, the stream is actually directed over the front portion of the belt, whence it runs over the forward edge of the belt onto the wire portion directly over the suction box 4. Substantially no splashing or eddying such as would impair the quality of the resulting paper should take place as the pulp suspension meets the forming wire. This can be ensured against by having the stream meet the wire at the proper machine-direction rate of flow, and by having the minimum cascading of the stream from the belt onto the wire. So, too, the application of suction onto the pulp suspension as soon as it contacts with the wire tends to quell any material turbulence which might otherwise ensue. Heretofore it was necessary to have the pulp in a highly watery or fluid condition for a substantial stretch of the wire before it reached the first suction box, as the shake of this stretch was relied upon for agitating at least some of the fibers crosswise, and the shake had this effect only with a fluent pulp wherein the fibers had freedom of motion or rearrangement. My

invention, therefore, makes possible the shortening of the wet end of the paper machine and an elimination of the shaking mechanism and its wear and tear on the machine.

The continuous stream of pulp suspension for the machine may be supplied from a flow-box 8 stationed in back of the breast-roll 2. The flow-box may continuously receive excess pulp suspension of the desired consistency, say $\frac{1}{10}$ to $\frac{1}{2}$ percent fiber content, from a pipe 9 leading from the stock regulator (not shown). The pulp suspension issues through a horizontal slot or so-called slice 10 in the front wall of the box, and flows over a slightly inclined sluice or channel 11, which directs the suspension over the front portion of the belt 6, as already described. The size of the slot 10 may be varied by a vertically adjustable gate 12 to govern the rate of discharge of the pulp suspension from the box. The excess pulp suspension in the box overflows the rear wall 13 into a rear compartment 14, from which the suspension gravitates through a pipe 16 to a storage tank or save-all (not shown) for reuse. The head of pulp suspension in the box and, accordingly, the rate of discharge from the box, may be determined by constructing the top portion of the rear wall 13 as a vertically adjustable dam 15.

Because the belt 6 tends to carry the stream of pulp suspension beyond the edge of the wire intersected by the diagonal resultant of stream motion, the sluice 15 is shown as being of considerably less width than the wire, and located midway between its edges, so that no matter how the belt is run, i. e., as indicated by arrow or in the opposite direction, there is sufficient width of wire on which the stream may be deposited and retained as it leaves the belt. If the belt is intended for running in only one direction, the sluice 15 may be of the same width as the wire, but its longitudinal center line should be offset sufficiently from the longitudinal center line of the wire toward that edge of the wire not intersected by the diagonal resultant of stream motion so that there is little or no loss of pulp suspension on account of its being discharged from the belt beyond the edge of the wire intersected by the diagonal resultant of stream motion. The tendency of discharging the pulp suspension beyond an edge of the wire is greatly reduced by the dewatering action which the pulp undergoes immediately upon striking the wire.

In Figure 3, the wire 20 is shown passing under a suction box 21 and then under a second suction box 22 spaced a substantial distance from the first suction box. Associated with the suction box 21 is a cross-feed belt 23, and with the suction box 22 a cross-feed belt 24, the belts moving in opposite cross directions, as indicated by arrow. Each belt has a sluice 25 and a flow-box 26 for the purpose hereinbefore described, the fibers being

5 deposited on the wire first as a layer or web whose fibers have an effective diagonal lay in one direction and then as a superposed layer or web whose fibers have an effective diagonal lay at right angles to the first diagonal lay. In other words, each lay may be at 45° to the machine-direction, but at 90° to each other. When such a paper is subjected to 10 tearing, it tends to produce a straight line of tear, whereas, on the other hand, in a paper all of whose fibers have an effective diagonal lay in only one direction, as previously described, the line of tear tends to drift toward this one direction of fiber lay.

15 The use of belts or their equivalent to impart a lateral component of motion to a stream of pulp suspension flowing continuously to and in the direction of movement of a moving web-forming instrumentality is 20 broadly my invention, whether the web-forming instrumentality takes the form of an endless wire cloth, such as used in a Fourdrinier machine, or whether it takes the form of a wire-cloth-covered roll or cylinder mould, 25 such as used in a cylinder machine. This component of motion imparted to the stream may be of such magnitude and in such a direction as to produce on the web-forming instrumentality a web in which the effective lay 30 of the pulp fibers is approximately 45° to the direction of movement of said web-forming instrumentality.

What I claim is:

1. In a method of making paper involving 35 the delivery of a continuous stream of pulp suspension to and in the direction of movement of a progressively moving web-forming instrumentality, that step which comprises continuously imparting to the stream immediately before it reaches said instrumentality a component of motion substantially perpendicular to the direction of motion of said instrumentality.

2. In a method of making paper involving 40 the delivery of a continuous stream of pulp suspension to and in the direction of movement of a progressively moving web-forming instrumentality, that step which comprises continuously imparting to the stream before 45 it reaches said instrumentality a component of motion substantially perpendicular to the direction of motion of said instrumentality, said component of motion being of such a magnitude as to produce a web in which the effective lay of the pulp fibers is approximately 45° to the direction of motion of said instrumentality.

3. In a method of making paper involving 50 the delivery of a continuous stream of pulp suspension to and in the direction of movement of a progressively moving web-forming instrumentality, that step which comprises continuously imparting to the stream immediately before it reaches said instrumentality a component of motion of such magnitude

and in such a direction as to produce a web on said instrumentality in which the effective lay of the pulp fibers is approximately 45° to the direction of motion of said instrumentality.

4. In a method of making paper involving 70 the delivery of a continuous stream of pulp suspension to and in the direction of movement of a progressively moving web-forming instrumentality, those steps which comprise continuously imparting to the stream immediately before it reaches said instrumentality, a component of motion of such a magnitude and in such a direction as to produce a web on said instrumentality in which the effective lay of the pulp fibers is approximately 45° to the direction of motion of said instrumentality, and partially dewatering said pulp immediately as it reaches said web-forming instrumentality.

5. The combination with a moving web-forming instrumentality and means for delivering a continuous stream of pulp suspension to and in the direction of movement of said instrumentality, of means for continuously imparting to said stream immediately before it reaches said instrumentality a component of motion of a magnitude and in a direction to cause the pulp fibers to assume an effective lay on said instrumentality of approximately 45° to the direction of motion of said instrumentality.

6. The combination with a moving web-forming instrumentality and means for delivering a continuous stream of pulp suspension to and in the direction of movement of said instrumentality, of means for continuously imparting to said stream immediately before it reaches said instrumentality a component of motion of a magnitude and in a direction to cause the pulp fibers to assume an effective lay on said instrumentality of approximately 45° to the direction of motion of said instrumentality, and means for dewatering the pulp as soon as it reaches said instrumentality.

7. The combination with a moving web-forming instrumentality and means for delivering a continuous stream of pulp suspension to and in the direction of movement of said instrumentality, of a belt passing directly under the stream immediately before it reaches the web-forming instrumentality and moving substantially at right angles to the direction of movement of said instrumentality.

8. The combination with the endless moving wire of a Fourdrinier machine and means for delivering a continuous stream of pulp suspension to and in the direction of movement of said wire, of a belt moving across said wire directly under said stream immediately before said stream reaches said wire.

9. The combination with the endless moving wire of a Fourdrinier machine and means

for delivering a continuous stream of pulp suspension to and in the direction of movement of said wire, of a belt moving across said wire directly under said stream immediately before said stream reaches said wire, and means for dewatering said pulp as soon as it contacts with said instrumentality.

10. The combination with the endless moving wire of a Fourdrinier machine and means 10 for delivering two continuous streams of pulp suspension to and in the direction of movement of said wire but at spaced intervals thereon, of a belt for each of said streams moving across said wire and directly under said 15 streams in opposite directions immediately before said streams reach the wire.

In testimony whereof I have affixed my signature.

JOHN C. SHERMAN.
